UNITED STATES PATENT OFFICE.

MOSES H. WILEY, OF BOSTON, MASSACHUSETTS, ASSIGNOR TO HIMSELF, JOHN H. B. LANG, AND THOMAS MILLER, OF SAME PLACE.

DESIGN FOR OIL-CABINETS.

Specification forming part of Design No. 5,271, dated September 19, 1871.

To all whom it may concern:

Be it known that I, Moses H. WILEY, of Boston, in the county of Suffolk and State of Massachusetts, have invented or produced a new and useful Design for an Oil-Cabinet; and do hereby declare the same to be fully described in the following specification and represented in the accompanying drawing, of which—

Figure 1 denotes a perspective view of an oil-cabinet constructed in accordance with my design. Fig. 2 is a similar view with the cover raised.

My said cabinet is divided horizontally into two compartments, the lower one constituting an oil-tank or reservoir, and the upper one an enclosure or sink to receive the pump and the various measures or vessels to receive the oil as it may be raised by the pump. In order to have the pump and its handle or elevating-piston extend a sufficient distance above the bottom of the sink to raise the desired amount of oil at a single elevation of the piston, the walls of the sink require to be of such height, if constructed in the ordinary manner—that is, of the same uniform height—as to render it very inconvenient to perform the various manipulations required in pumping, measuring, and filling the cans or other

vessels. In order to remedy this defect, I form the top or cover portion of the cabinet inclining its front so that its extreme front edge is but a few inches above the bottom of the sink, whereby ready access is had to the pump, and the various manipulations in measuring and filling the oil-vessels can be performed with great facility.

In the drawing, A denotes the body of the cabinet, which is of a rectangular shape, and divided into two compartments by means of a horizontal partition, B. The upper part of the superior compartment has its walls formed sloping toward its front. C is the cover or lid of the cabinet, which is hinged thereto so as to be opened or closed, as may be desirable. In case the cabinet is of considerable length two lids may be used.

Having described my invention, what I claim is—

The design for an oil-cabinet, consisting of the body A formed with the inclined front, the inclined cover C, and the horizontal partition B, as herein set forth and shown.

MOSES H. WILEY.
